United States Patent Office

Des. 213,602
Patented Mar. 18, 1969

213,602

TIERED PARTS BIN

William D. Taylor, Wooster, Ohio, assignor to Rubber-maid Incorporated, Wooster, Ohio, a corporation of Ohio

Filed Nov. 6, 1967, Ser. No. 9,296

Term of patent 14 years

The portion of the term of the patent subsequent to June 25, 1982, has been disclaimed

U.S. Cl. D87—1
Int. Cl. D6—01

FIG. 1

FIG. 2

FIG. 3

FIG. 4

FIG. 1 is a perspective view of a tiered parts bin embodying my new design.

FIG. 2 is a top plan view thereof.

FIG. 3 is a side elevation thereof.

FIG. 4 is a plan sectional view on line 4—4 of FIG. 3.

I claim:

The ornamental design for a tiered parts bin, as shown.
